Primary Examiner — Darlington Ly(74) *Attorney, Agent, or Firm* — Daryl R. Wright; Greg Carr**CLAIM**

I claim the ornamental design for a bumper for a model vehicle, as shown and described.

DESCRIPTION

FIG. 1 is a bottom, front, and right side perspective view of a bumper for a model vehicle showing my new design;
 FIG. 2 is a rear elevation view thereof;
 FIG. 3 is a front elevation view thereof;
 FIG. 4 is a left side elevation view thereof;
 FIG. 5 is a right side elevation view thereof;
 FIG. 6 is a top plan view thereof;
 FIG. 7 is a bottom plan view thereof; and,
 FIG. 8 is a top, front, and left side perspective view thereof. The broken lines in the drawings illustrate portions of the bumper for a model vehicle that form no part of the claimed design.
